REVERSIBLE TWO-STROKE INTERNAL
COMBUSTION ENGINEEdvin Ossian Parcival Thege and Olof Verner
Fixén, Stockholm, Sweden, assignors to Aktie-
bolaget Atlas-Diesel, Stockholm, SwedenApplication July 17, 1939, Serial No. 284,824
In Sweden November 29, 1938

13 Claims. (Cl. 123—41)

The present invention relates to reversible two-stroke internal combustion engines having a scavenging pump of the centrifugal compressor type driven by the engine.

Since scavenging pumps of the said type must be driven in a certain direction of rotation, it has hitherto been necessary, when reversing the engine, also to reverse the direction of rotation of the pump, so that independent of the changed direction of rotation of the engine the pump maintains its active direction of movement.

To this end a reversing gear must be included in the transmission gearing between the engine shaft and the pump shaft, which makes it necessary to use a great number of movable parts resulting in a greater risk of running disturbances, and, besides, the length of the engine construction will be rather great. Further, the reversing gear brings about a complication of the manoeuvring means of the engine, and thus also the risk of incorrectly performed manoeuvring operations will be increased. A still further drawback in using a reversing gear consists in this that it generally brings about a rather disturbing noise, substantially resulting from the intermeshing gear wheels.

The present invention has for its object to avoid the said drawbacks and consists substantially in this that the scavenging pump comprises two centrifugal compressors, one of which is made to be active when running the engine in the one direction and the second when running the engine in the opposite direction. The two compressors, which for instance may form a twin-pump, may preferably be driven in the same direction and provided with bucket vane wheels active in opposite directions. However, it is also possible to drive the two compressors in opposite directions, in which case the bucket vanes of the two wheels have to be equally directed, so that one pump only will be active at each direction of rotation of the engine. The two pumps may preferably, by means of valve devices, be alternately connected to the scavenging air receiver of the engine.

By such means it is obtained that independent of the direction of rotation of the engine one of the centrifugal compressors will be active, whereas the second compressor idles in the backward direction. The power required for the idling of one of the compressors in the backward direction is very small and amounts to the ventilation work only of the vane-wheel or -wheels of the compressor and is generally less than the loss of efficiency of a reversing gear.

In such cases, where the engine at the backward running needs not develop full power, the centrifugal compressor adapted for the said direction of rotation can be made smaller than that adapted for the forward running, and by 5 such means the loss of power due to the co-rotation of the said compressor at the forward running, the main direction of rotation, will be further decreased.

On the accompanying drawings some embodiments of an arrangement according to the invention are shown diagrammatically. Fig. 1 is a side view of part of the engine, the scavenging pump according to one form of embodiment being shown in axial section. Fig. 2 is a top 15 view of the arrangement according to Fig. 1, and Fig. 3 illustrates diagrammatically part of the pressure conduits of the scavenging air receiver. Figs. 4 to 6 are similar views showing a scavenging pump according to a modified arrangement. Figs. 7 and 8 are views similar to those of Figs. 4 and 5 and show an embodiment, in which the two compressors are driven in opposite directions. Fig. 9 illustrates diagrammatically two separate valves in the pressure 25 conduits of the compressors. Figs. 10 and 11 show diagrammatically two different embodiments of means for automatically controlling the air-flow from the compressors.

In Figs. 1 and 2, 1 designates part of the combustion engine and 2 the crank shaft thereof, the free end of said shaft being mounted in a projecting part 3 of the crank casing carrying the frame 4 of the scavenging pump. The pump consists of two separate housings 5 and 6, respectively, having associated helices 7 and 8, respectively, and bucket vane wheels 9 and 10, respectively, which are secured to a common shaft 11 mounted in the pump frame 4. The air intake of the pump 5, 7, 9 is denoted by 12 and 40 that of the pump 6, 8, 10 by 13. The pressure conduit connected to the helix 7 of the former pump is denoted by 14 and the pressure conduit connected to the helix 8 of the second pump by 15. The said two pressure conduits 14 and 15 45 are in communication with a common pressure conduit 16 communicating with the scavenging air receiver 17 of the engine. As apparent from Fig. 3, a flap valve 18 is mounted in the common pressure conduit 16 at the connecting place of 50 the pressure conduits 14 and 15, and by means of the said valve the one or the other of the conduits 14 and 15 can be shut off from the conduit 16. The two pumps are driven from the engine shaft 2 by means of a toothed wheel gearing 19, 55

20, 21, 22 located between the pumps, the shafts of the intermediate wheels 20, 21 being mounted in the pump frame 4.

The pump 5, 7, 9 is assumed to be adapted 5 for forward running and the pump 6, 8, 10 for backward running. Thus, in the former case the pump 5, 7, 9 is active and forces the air through the conduit 14, whereby the flap valve 18 shall take up the position shown by full lines 10 in Fig. 3, so that the air enters the receiver 17 through the conduits 14 and 16, the conduit 15 being shut off. In this case the pump 6, 8, 10, the bucket vanes of which are turned in a direction opposite to that of the vanes of the pump 15 5, 7, 9, is inactive.

When reversing the direction of rotation of the engine 1 from forward to backward running also the direction of rotation of the pumps is reversed, and the pump 6, 8, 10 will be active, 20 whereas the pump 5, 7, 9 will be inactive. In this case the flap valve 18 shall be moved to the position shown by dotted lines in Fig. 3, so that a free communication is obtained between the conduits 15 and 16 and simultaneously the pipe 25 14 is shut off.

The embodiment shown in Figs. 4 to 6 differs from that one above described in this respect only that here the two pumps 5, 7, 9 and 6, 8, 10 are provided with a common air intake 23 located between the pumps and that the toothed gearing 19 to 22 is located at the inside of the pump unit between said unit and the engine. The action of this arrangement is the same as that of the embodiment according to Figs. 1 to 3.

35 The embodiment shown in Figs. 7 and 8 differs from that one according to Figs. 4 and 5 in this respect that the two bucket vane wheels 9 and 10, the vanes of which are to be equally directed, are placed on separate shafts 11a and 11b, respectively, mounted in the frame 4 and driven from the engine shaft 2 through separate gearings 24, 25, 26 and 19 to 22, respectively. As visible from Fig. 7 the gearing driving the vane wheel 9 contains three gear wheels 24, 25 and 26, whereas the 45 gearing driving the vane wheel 10 contains four gear wheels 19, 20, 21 and 22. As a consequence, the shaft 11a and the vane wheel 9 will obtain the same direction of rotation as that of the engine shaft 2, whereas the shaft 11b and the vane wheel 50 10 will be caused to rotate in the opposite direction. Thus, since the vanes of the two wheels 9 and 10 are equally directed, the two compressors will be alternately active, the one at the running of the engine in the one direction and the other at 55 the opposite direction of running.

If desired, separate flap valves may obviously be placed in each one of the pressure conduits 14 and 15 as shown at 18a and 18b in Fig. 9, the valve bodies being pivotally connected by a rod 27 so 60 that when closing the one valve the other will be opened and vice versa, and the valves need obviously not have the shape of flap valves, but may be of any desired construction.

If desired, the adjustment of the valves may be 65 performed automatically at the reversing of the engine through the air pressure from the temporarily active compressor or also by the aid of mechanical, pneumatic or hydraulic means of any suitable construction.

70 Fig. 10 shows an embodiment, in which a single flap valve 18c is pivotally connected at 28 at the place of connection of the pipes 14, 15 and 16, similar to the embodiment shown in Fig. 3. The 75 weight of the valve body 18c is balanced by a counter-weight 29 secured to the valve by means

of a lever arm 30. If the compressor communicating with the pipe 15 be active, the air forced through said pipe will turn the valve to the position shown by full lines, whereas, if the other compressor forcing air through the pipe 14 be active, the valve will obtain the position shown by dotted lines, the pipe communicating with the temporarily idling compressor being shut off.

Fig. 11 illustrates diagrammatically fluid-operated (pressure-oil or pressure-air) means for adjusting the valve 18d. The said valve is pivotally connected at 31 at the place of intersection of the pipes 14, 15 and 16 and has a lever arm 32 connected to it, which by means of a rod 33 is operatively connected to a piston 34 capable of reciprocating in a cylinder 35 having inlet pipes 36 and 37, respectively, for a pressure fluid opening at both ends of the cylinder. The said pipes also open into a cylindrical valve housing 38 at both ends of the same, a valve body 39 being capable of reciprocating in said housing and being connected to a manoeuvring lever 40 by means of a rod 41. A pressure fluid from any suitable source of pressure is supplied to the valve housing 38 through a pipe 42.

In the valve position shown, the pressure fluid enters into the cylinder 35 through the pipe 36 at the right-hand end causing the piston 34 to move to the left-hand end as shown, thereby causing the valve 18d to take up the position shown by full lines closing the pipe 14 and opening the pipe 15. If the valve 38 be moved towards the right by operating the lever 40, the pressure fluid will enter at the left-hand end of the cylinder 35 through the pipe 37 and moves the piston 34 towards the right, so that the flap valve 18d will close the pipe 15 and open the pipe 14, thereby establishing communication between the pipes 14 and 16 instead of between the pipes 15 and 16 as in the former position. Obviously, the piston valve 38 may be in connection with the reversing means of the engine, so that the flap valve 18d will be operated automatically when reversing the engine.

On the annexed drawings the centrifugal compressors have been shown as one-wheeled, one-stage compressors, which, however, is not necessary, since the same may be made with a plurality of wheels as multi-stage compressors without departing from the scope of the invention. Besides, the compressors may be placed at other places with respect to the engine, such as for instance at the one side of the engine, without the manner of driving the compressors being thereby altered.

What we claim is:

1. A reversible two-stroke internal combustion engine and a scavenging pump of the centrifugal compressor type driven by said engine, said pump comprising two centrifugal compressors, the one being arranged to be active in the one direction of running of the engine and the second in the opposite direction of running.

2. A reversible two-stroke internal combustion engine and a scavenging pump of the centrifugal compressor type driven by said engine, said pump comprising two centrifugal compressors, the one being arranged to be active in the one direction of running of the engine and the second in the opposite direction of running, said compressors being rotated in the same direction and provided with bucket vane wheels active in opposite directions of rotation.

3. A reversible two-stroke internal combustion engine and a scavenging pump of the centrifugal compressor type driven by said engine, said pump

comprising two centrifugal compressors, the one being arranged to be active in the one direction of running of the engine and the second in the opposite direction of running, said compressors being rotated in opposite directions and provided with bucket vane wheels having equally directed vanes.

4. A reversible two-stroke internal combustion engine, a scavenging pump of the centrifugal compressor type driven by said engine, said pump comprising two centrifugal compressors made as a twin-pump, and a shaft common to both compressors, one of which is arranged to be active in the one direction of running of the engine and the second in the opposite direction of running.

5. A reversible two-stroke internal combustion engine, an air receiver on said engine, a scavenging pump of the centrifugal compressor type driven by said engine, said pump comprising two centrifugal compressors, and valve means for alternately bringing said compressors in communication with said air receiver, one of said compressors being arranged to be active in the one direction of running of the engine and the second in the opposite direction of running.

6. A reversible two-stroke internal combustion engine, an air receiver on said engine, a scavenging pump of the centrifugal compressor type driven by said engine, said pump comprising two centrifugal compressors, and automatic valve means for alternately bringing said compressors in communication with said air receiver, one of said compressors being arranged to be active in the one direction of running of the engine and the second in the opposite direction of running.

7. A reversible two-stroke internal combustion engine and a scavenging pump of the centrifugal compressor type driven by said engine, said pump comprising two centrifugal compressors, the one being arranged to be active in the one direction of running of the engine and the second in the opposite direction of running, said compressors having separate air intakes.

8. A reversible two-stroke internal combustion engine and a scavenging pump of the centrifugal compressor type driven by said engine, said pump comprising two centrifugal compressors, the one being arranged to be active in the one direction of running of the engine and the second in the opposite direction of running, said compressors having a common air intake.

9. A reversible two-stroke internal combustion engine, a shaft driven by said engine, a scavenging pump of the centrifugal compressor type comprising two centrifugal compressors, and a common transmission gearing between said shaft and said compressors, one of which is arranged to be active in the one direction of running of the engine and the second in the opposite direction of running.

10. A reversible two-stroke internal combustion engine, a shaft driven by said engine, a scavenging pump of the centrifugal compressor type comprising two centrifugal compressors, and a common transmission gearing between said shaft and said compressors, one of which is arranged to be active in the one direction of running of the engine and the second in the opposite direction of running, said transmission gearing being located between the said two compressors.

11. A reversible two-stroke internal combustion engine, a shaft driven by said engine, a scavenging pump of the centrifugal compressor type comprising two centrifugal compressors, and a common transmission gearing between said shaft and said compressor, one of which is arranged to be active in the one direction of running of the engine and the second in the opposite direction of running, said transmission gearing being located between the engine and the pump.

12. A reversible two-stroke internal combustion engine, a shaft driven by said engine, a scavenging pump of the centrifugal compressor type comprising two centrifugal compressors and separate transmission gearings between said shaft and said compressors for driving the latter in opposite directions, one of said compressors being arranged to be active in the one direction of running of the engine and the second in the opposite direction of running.

13. A reversible two-stroke internal combustion engine and a scavenging pump of the centrifugal compressor type driven by said engine, said pump comprising two centrifugal compressors, the one being arranged to be active in the one direction of running of the engine and the second in the opposite direction of running, the compressors adapted for the forward running of the engine being made larger than that one adapted for the backward running.
